SASH BALANCE CONNECTOR

Alvin R. Larson, Stamford, Conn., assignor to Unique Balance Co., Inc., New York, N. Y., a corporation of Illinois

Application February 23, 1955, Serial No. 490,052

6 Claims. (Cl. 16—197)

This invention relates to connectors for securing spring sash balances to window sashes and, more specifically, to an improved connector by means of which the movable portion of spring balances of the spiral type may be effectively joined to window sash.

Spring balances of the spiral rod type, such as disclosed in the Patents Nos. 1,926,951 and 2,041,646 to Larson, must be secured at one end to a window jamb and at the other end to sash carried in the jamb by the balances. In one type of spiral sash balance, a drive screw or the like fastens the spiral rod to the jamb and in this instance, the torsion spring must be secured by suitable structure to the sash. Normally, the spiral rod in this type of balance extends below the structure employed to connect it to the sash.

Formerly, the structure joining the balance to the sash has been in the form of a connector comprising a strip pivoted on a collar formed for attachment to a member joined to the torsion spring. In order to insert the balance in a sash groove adjacent to the jamb, the connector strip was pivoted to orient it parallel to the balance and the balance secured to the jamb. Subsequently, it was necessary to secure the connector to the sash and in order to accomplish this function, the connector required a heavy force to displace it downwardly a substantial distance so that it could be pivoted without interference from the spiral rod. This was a difficult and dangerous operation, particularly when heavy sashes were involved which necessitated the use of a tension spring in the balance in addition to the torsion spring, because the pull that had to be exerted on the connector equaled one-half the weight of the sash. To exert this force in a limited and inconvenient working area in order to displace the connector while supporting the heavy sash raised many problems in the installation of such sash.

Accordingly, it is an object of the present invention to provide an improved connector for effectively and conveniently securing a sash balance to a sash.

It is another object of the invention to provide a sash connector having the above characteristics which may be secured to sash having any desired configuration at the point of attachment.

These and further objects of the invention are accomplished by providing a sash connector comprising a flexible strip adapted to be mounted by suitable structure on an extensible member joined to a movable portion of a sash balance. In a preferred embodiment of the invention, a locating tab is formed on the strip. In addition, suitable apertures and wood holding prongs are provided on the flexible strip for securing it to a sash.

These and further objects and advantages of the invention will be more readily understood when the following description is read in connection with the accompanying drawings in which:

Figure 1 is an elevation, partially broken away, of a mounted spring sash balance of the spiral rod type joined

2

to a sash by a connector constructed in accordance with the principles of the present invention;

Figure 2 is a transverse section of the elevation illustrated in Figure 1 taken on the view line 2—2 looking in the direction of the arrows;

Figure 3A is a fragmentary elevation, partially broken away, illustrating a modified sash connector in accordance with the present invention;

Figure 3B is a fragmentary elevation, similar to Figure 3A but showing the sash in greater detail, illustrating the manner in which the modified sash connector may be secured to a sash having an unusual configuration;

Figure 4 is a transverse section of the flexible strip of Figure 3A taken on the view line 4—4 looking in the direction of the arrows; and

Figure 5 is another transverse section of the flexible strip and a portion of the sash of Figure 3B taken on the view line 4—4 looking in the direction of the arrows.

Referring to an illustrative embodiment of the present invention in greater detail with particular reference to Figures 1 and 2, a spiral sash balance 10 is secured by a drive screw 11 and a stand-off collar 11a to a window jamb 12 in a groove 13a of a sash 13. A tube 14, pierced at its upper end by an eyelet 15, encloses the remaining elements of the balance 10 when it is retracted. A loop 16, constituting the upper end of an extensible coil spring 17, is supported by the eyelet 15 while a spiral rod 18, bent back on itself to form a loop 19, is secured to the upper end of the spring 17. A stop rivet 20, provided on the lower end of the spiral rod 18, prevents its disengagement with a conventional following nut (not shown) attached to the upper end of a torsion spring 21.

A generally cylindrical member 22, securely fastened to the lower ends of both the torsion spring 21 and the tension spring 17, has formed on its lower edge an annular collar 23, best shown in Figure 2, carrying a pair of upwardly extending ratchet elements 24.

In order to operatively join the spring carrying member 22 to the sash 13, a connector 25 is adapted to be fastened to both of these elements. The connector 25 comprises an outer split collar 26, preferably integral with a flexible strip 27 carrying on its opposite sides a pair of wood holding triangular prongs 27a extending substantially perpendicularly from the surface of the strip and each of them formed with a slight curl, as shown in Figure 4. The prongs 27a are preferably canted toward the free end of the strip 27. The strip 27 is completed by a plurality of apertures 28 receiving screws 28a. Secured to the inner surface of the split collar 26 is a ring 29 carrying ratchet elements 30 on its lower edge which cooperate with the ratchet elements 24 to maintain the tension of the torsion spring 21.

The strip 27 is sufficiently flexible so that it may be bent to conform to the shape of the lower edge of the sash 13. For example, it may be formed of metal such as a relatively soft steel. The flexibility of the strip 27 is clearly shown in Figure 3B in which a sash 13', similar in other respects to the structure illustrated in Figure 1, is provided with a horn-like lower portion 31 both to strengthen the sash and improve its appearance.

Referring more specifically to Figures 3A and 3B, the flexible strip 27 carries a locating tab 27b at its upper end extending toward the sash 13'. The tab 27b may be formed in any desired manner such as, for example, by punching it from the strip 27. Since the flexible strip 27 may be bent to conform to the configuration of the portion 31, it is unnecessary to employ a special connector as was often the case prior to this invention.

Examining the manner in which the connector illustrated in Figure 1 may be employed, initially the strip 27 extends downwardly as shown by the broken lines in

Figures 1 and 3 to permit the insertion of the balance 10 into the groove 13a provided on the sash 13. After securing the balance to the jamb 12 by the screw 11, the sash 13 is raised to its uppermost position and the strip 27 bent to engage its lower edge. This operation serves to hold the sash 13 in position when the strip 27 is formed of a sufficiently strong material, a preferable construction. Next, the prongs 27a may be driven into the sash 13 and due to their forward cant, they will have a tendency to pull the connector 25 downwardly in the groove 13a. This results in the slight separation of the connector 25 and the tube 14 shown in Figure 1. In addition, the curl of the prongs 27a will cause them to bend and clinch the wood, as shown in Figure 5, to securely fasten the strip 27 to the sash 13. This frees both hands for the insertion of the screws 28a through the apertures 28 into the sash 13.

In certain instances, it is desirable to prestress the balance 10 in order to eliminate any possibility that the sash 13' will sag from its highest position. This is achieved by using the connector shown in Figures 3A and 3B, the balance 10 and the sash 13' initially being positioned as shown in Figure 3A. In order to fasten the connector 25 to the sash 13', it is displaced downwardly a short distance sufficient to hook the tab 27b under the lower edge of the sash 13', this action stressing the balance 10. It will be evident that the position of the tab 27b on the strip 27 determines the degree of extension of the balance 10 so that prestressing is effectively limited, measured and controlled. When the flexible strip 27 is subsequently bent to conform to the lower edge of the sash 13' (Figure 3B), the tab 27b is received in the opening from which it was initially punched. Since the balance 10 will be under stress when the sash 13' is at its highest position, sash sagging will be effectively precluded with this arrangement.

It is evident that the above-described methods of fastening the balance 10 to the sashes 13 and 13' are both simple and safe. It provides many advantages over the former fastening methods in which the connector comprised a pivoted strip extending on the other side of the spiral rod 18. As mentioned above, such an arrangement necessitated the extension of the balance until such strip was below the spiral rod, pivoting it to engage the sash and then fastening it to the sash, a difficult and dangerous operation obviated by the present sash connector.

It will be apparent that while the present invention is particularly applicable to spring balances used with heavy sash, it may be employed with other spring balances in order to simplify their attachment to sashes. Furthermore, while ratchet elements are employed to couple the typical embodiment of the sash connector described above to the spring balance, it will be apparent that other modes of coupling such as a rigid connection may be used to secure the connector to the balance. Moreover, it will be understood that the above-described embodiments of the invention are illustrative only and modifications thereof

will occur to those skilled in the art. Therefore, the invention is not to be limited to the specific apparatus disclosed herein but is to be defined by the appended claims.

I claim:

- 5 1. A sash balance connector for spring balances of a spiral rod type in which the spiral rod normally extends below a movable element of the balance, said connector comprising an end portion adapted to be joined to the movable element, a flexible strip joined to the end portion and normally extending in the direction of movement of the movable element between the sash edge and the extending spiral rod, the flexible strip adapted to be bent to engage and conform to the lower edge of the sash, and means on the strip for securing it to the sash.
- 10 15 2. A device as defined in claim 1 in which a locating tab adapted to be hooked under the lower edge of the sash extends substantially perpendicularly from the end of the flexible strip joined to the end portion.
- 20 3. A device as defined in claim 1 wherein said securing means includes a pair of forwardly canted laterally curled prongs extending substantially perpendicularly from the surface of the strip, said prongs adapted to be driven into the lower edge of the sash.
- 25 4. A sash balance connector for spring balances of a spiral rod type in which the spiral rod normally extends below a movable element of the balance, said connector comprising a cylindrical portion with first ratchet means adapted to be joined to the movable element having co-operating second ratchet means, a flexible metal strip joined to the cylindrical portion and normally extending in the direction of movement of the movable element between the sash edge and the extending spiral rod, the flexible strip adapted to be bent to engage and conform to the lower edge of the sash, and means on the strip for securing it to the sash.
- 30 35 5. A device as defined in claim 4 in which a locating tab adapted to be hooked under the lower edge of the sash extends substantially perpendicularly from the end of the flexible strip joined to the cylindrical portion.
- 40 6. A device as defined in claim 4 wherein said securing means includes a pair of forwardly canted laterally curled prongs extending substantially perpendicularly from the surface of the strip, said prongs adapted to be driven into the lower edge of the sash.
